(57) CLAIM

I claim the ornamental design for a horizontal seat organizer with removable dividers for vehicle, as shown and described.

DESCRIPTION

FIG. 1 is a perspective view of a horizontal seat organizer with removable dividers for vehicle showing my new design;

FIG. 2 is a top plan view thereof;

FIG. 3 is an end elevational view thereof, the elevational view of the opposing end being a mirror image thereof;

FIG. 4 is a side elevational view thereof; and,

FIG. 5 is an elevational view of the opposing side.

All views show the lid/writing platform in an opened condition.
